UNITED STATES PATENT OFFICE.

THOMAS BIBBY, JAMES BIBBY, AND JOHN BARON, OF BURNLEY, AND WILLIAM BARON, OF ROCHDALE, ENGLAND.

IMPROVEMENT IN PAPER-BAG MACHINES.

Specification forming part of Letters Patent No. 131,841, dated October 1, 1872.

To all whom it may concern:

Be it known that we, THOMAS BIBBY, JAMES BIBBY, and JOHN BARON, all of Burnley, in the county of Lancaster, and WILLIAM BARON, of Rochdale, in the same county, Kingdom of Great Britain and Ireland, have invented certain Improvements in Machinery or Apparatus to be Employed for Manufacturing Paper Bags, for which Letters Patent of the Kingdom of Great Britain and Ireland, were granted to us August 24, 1871, of which the following is a specification:

The invention is designed for the purpose of manufacturing that description of paper bag used in stores, having a square formation at the bottom; and consists in a novel arrangement of mechanism, the construction and action of which will be more readily understood in connection with the following description on reference to the accompanying drawing. It is designed to construct the bags by this machine out of a continuous tube of paper that has been previously constructed by any well-known paper-tube making machine.

In the drawing hereunto attached, Fig. 1, Sheet 1, represents a longitudinal section of the machine employed for manufacturing paper bags out of a continuous paper tube; in Sheet 2, Fig. 2 represents a general elevation of the machine, and Fig. 3 represents a detached reverse elevation of that portion of the driving apparatus giving the intermittent feed or traverse to the paper tube, sufficient with each movement for the construction of one bag; Fig. 4, Sheet 3, represents a general plan view of the machine; and in Sheet 4, Figs. 5 and 6 represent transverse sections of Fig. 1; Fig. 7 represents a longitudinal section in elevation of the box or block upon which the bag is formed; Fig. 8 represents a detached front end of the box contracted; Figs. 9 and 10 represent, respectively, the end views of Figs. 7 and 8; Fig. 11 represents a plan view of the general arrangement of mechanism comprising the box or block, together with the fingers and wedges actuating the contracting and expanding portion of the front end of the box, the dotted portion thereof showing the position the wedges and fingers assume when the box is in its contracted state; Figs. 12, 13, 14, and 15, respectively, represent diagrams illustrat-

ing the various positions the closing-in rollers or folders assume with respect to the paper tube when closing in the bottom of Fig. 16 represents the bottom of the bag when folded; Fig. 17 represents the two positions of the V-templets; and Fig. 18, Sheet 3, represents a view of the bag when completed and delivered from the machine.

In order that the operation of the machine may be clearly understood, we will go through the complete process of formation of one bag, assuming for this purpose that the machine with its various movements is in the position shown in Sheets 1, 2, and 3—that is, at the time of severing a bag of a given length from the tube. At this time the shears *a a*, (seen more clearly in Sheet 4, Fig. 5,) actuated by the cam *a¹* through the medium of the levers *a²* and slide *a³*, come into action, and in their process of severing contract the surfaces of the tube, as seen in the same figure; while in this position the pasters *b b*, actuated by the cam *b¹*, levers and connecting-rods *b²*, are raised from their paste-trough *b³*, so as to come into contact with portions of the overlap of the paper tube that subsequently form the surfaces of adhesion when closed in. During this operation the box or block upon and against which the bag is formed, together with its internal and external mechanism employed in the bag's formation, may be thus described: While the overlap end of the tube was being severed and pasted, as before described, the block end of the box, constructed of movable bent surface-plates *c c*, are in their contracted position, so as to allow of the free delivery of the tube when being sheared from the continuous length, and also for the action of the pasters on the overlap. This contraction and expansion of the surface-block end of the box, the expansion of which into its full square or rectangular shape, takes place immediately after the pasting operation is complete, is effected by the lever-wedges *c¹ c¹*, which, when causing the surface-block ends to expand, are forced in between the center end plates thereof, as seen in Sheet 4, Figs. 9 and 10, the in-and-out motion of which is transmitted thereto by the cam *c²*, through the medium of the vertical swivel-rods *c³ c³*, and levers *c⁴*. The expansion of these surface-plates gives a full square forma-

tion to the paper tube, in which state its overlap is now prepared to be acted on, so as to form the bottom of the bag. Immediately after the movable block-surface plates *c c* are fully distended, the cam *d*, through the medium of the lever *d¹* and sliding bars *d²*, brings the bowl *d³* outside of the paper tube into contact with the internal bowls *d⁴*. These bowls when acted upon so as to become depressed, as described, force out by means of the bell-crank lever *d⁵* and rods *d⁶*, the two V-templets *d⁷ d⁸* from the top and bottom surface-plates of the box, as seen in Sheet 4, Fig. 12, the extent of their movement outward being equal to the overlap of the paper bag. During the time the V-templets remain in this extended position the right-hand side folding-rollers *e e* are caused to advance, as seen in Sheet 4, Fig. 13, so as to fold in the right side of the overlap, and when receding the left-hand side folding-rollers *f f* are likewise caused to go through the same process and fold in the left side of the overlap, the advance and retiring action of which are obtained by the cams *e¹* and *f¹*, Sheet 4, Fig. 5, through the medium of the levers *e²* and *f²* and the connecting sliding-bars *e³* and *f³*. So soon as the two sides are folded in, and while the folding-rollers are being fully withdrawn by the action of their respective mechanism, hereinbefore described, the V-templets, by the continued action of their acting mediums, are withdrawn so as to leave the surface at the end of the box clear, and the top and bottom V-shaped ends of paper standing out in the positions left by the templets. The under folding-rollers *g g*, at this time acted upon by the cam-levers and slides *g' g'*, now come into operation and fold in the bottom V-shaped overlaps of the bag containing the paste, as seen in Sheet 4, Fig. 14, the rolling action of which at the same time distributes the paste over such V-surface. When this process is completed, and as the folding-rollers *g g* are receding, the top folding-rollers *h h* are caused to advance through the medium of the cams, levers, and slides *h'*, and fold in the top overlap over the under pasted surface, as seen in Sheet 4, Fig. 15, the action of which completes the folding formation of the bottom of the bag. The movable surface-plates *c c* of the bottom of the block or box, during the foregoing operation, are maintained in their extended position by reason of the wedges *c' c'* being fully inserted between them; but immediately after the folding-in is completed, as described, the mechanism actuating the wedges releases the same and allows the springs *i* to contract the movable surface-plates, as seen in Sheet 4, Fig. 8, allowing thereby a freedom of action to the mechanism subsequently employed for completing and finally delivering the bag from the machine. During the foregoing operations the driving-shaft *m* transmits motion through the pinion *k*, carrier *l*, and connecting-rod *j* to the arm *n*, which regularly withdraws in its vibration sufficient tube from the supply-reel *o*,

which will allow a motion free from strain to the tube-feeding apparatus, the action of which now takes place, and which will be more readily understood on reference to Figs. 7 and 11, Sheet 4. As before stated, immediately after the movable surface-plates of the box or block assume their contracted position the tube must be delivered and severed at a point equal to the length of one bag. This is accomplished as follows, (see Sheet 2, Fig. 6:) The bowl *p* on the rim-disk *q*, keyed to the driving-shaft *n*, as it revolves comes into contact with one of the four arms of the star-wheel *r* secured to the gear-wheel *r'* revolving on the stud *s*, the action of which moves such star-wheel one-quarter of a revolution, in which position it is held by a detent, *q'*. The motion being transmitted to the miter-gearing and vertical shafts *t* gives motion to the feed-pulleys *u*, (or it will be evident that, in lieu of the star-wheel, cams or other equivalent giving an intermittent motion may be employed with a similar result.) The motion thus given causes the feed-pulleys to revolve and deliver from the end of the box, intermittently, a length of tube sufficient for the depth of one bag and overlap for the subsequent formation of the bottom portion of the next bag. Simultaneously with the severing of the bag from the tube the platform or table *n'* upon which it is delivered is raised into an inclined position by means of the tappet *v* and lever *v'*. The tucker or bent creasing-lever *w* also comes into action at this time and tucks in or creases the bag so as to cause a part of its folded bottom portion to fall back and lie in a position on a level with the remaining portion of the bag. This tucking action also impels the severed bag forward between the pressing-rollers *x x*. The revolving of these rollers is obtained through the medium of the shaft *y* and bevel-gearing *z*. The bag when passing between these rollers becomes pressed ready for packing, but before leaving the machine it is received by the printing-rollers *s¹* and *s²*, which are caused to revolve in unison with the calendering-rollers. The roller *s¹* is supplied with type or other equivalent representing subject-matter, and the bottom roller *s²* with printer's cloth. The position of the type upon the printing-roller or cylinder allows the thick or folded portion of the bag to get through first, after which its type, being previously inked by the rollers *s³* from the ink-trough *s⁴*, prints or impresses upon the flat front surface of the bag any subject-matter desired, at the same time delivering the complete bag from the machine.

Having now described the nature of our invention, together with the method of carrying the same into practical effect, we wish it to be understood, in conclusion, that we do not wish to confine ourselves to the precise details hereinbefore described so long as the general features and principle of the several actions composing the machine, as a whole, are retained; but—

What we more particularly desire it to be

understood that we claim as new in our arrangement of mechanism, is—

1. The combination of the former, to which are hinged plates *c c*, the devices for operating said plates and for passing a continuous tube of paper over the former, and the severing and pasting devices specified, or their equivalents, for the purpose set forth.

2. The combination of the sliding V-shaped plates *d'* and lateral reciprocating rolls *e e*, operating to fold the end of the tube between the plates, as set forth.

3. The combination of the plates *d'* operating as described, and the reciprocating rolls *e* and *f, g* and *h*, as set forth.

4. The combination, with the feed-rolls, of the disk *g*, bowl *p*, star-wheel *r*, detent *q'*, and intermediate gearing or their equivalents, as and for the purpose set forth.

5. The combination of the tucker *w*, rolls *x*

x, and table *n'* hinged at one end, and operated by the devices described or their equivalents, so as to coincide with the inclined side of the bag, as set forth.

6. The combination of devices for feeding a continuous tube and a former over which the tube is passed, and which contracts during the movement of the paper, and which, after the tube is severed, expands and forms a platen upon which the end of the tube may be folded, as specified.

In testimony whereof we have signed our names to this specification in the presence of two subscribing witnesses.
